CLAIM

The ornamental design for bookcase or the like, substantially as shown and described.

DESCRIPTION

FIG. 1 is a front elevational view of a bookcase or the like showing my new design;

FIG. 2 is a right side elevational view, the left side being a mirror image thereof;

FIG. 3 is a top plan view; and

FIG. 4 is a front and left side perspective view.

The rear of the bookcase or the like is plain and unornamented.
